SLICING DEVICE

Edwin L. Storer and Albert H. Cox, Tulsa, Okla.

Application March 21, 1934, Serial No. 716,697

4 Claims. (Cl. 31—5)

This invention relates to a slicing device and has for the primary object the provision of means whereby cheese or like food products which are made in block formation may be readily severed into slices and which will sever a plurality of slices during each cutting operation and also whereby the food product may be cut into slices of different thicknesses.

Another object of the invention is the provision of means whereby small pieces or ends of the food product may be severed into slices and thereby eliminate waste.

With these and other objects in view this invention consists in certain novel features of construction, combination and arrangement of parts to be hereinafter more fully described and claimed.

For a complete understanding of our invention, reference is to be had to the following description and accompanying drawings, in which

Figure 1 is a top plan view, partly in section, illustrating a slicing device constructed in accordance with our invention.

Figure 2 is an end elevation illustrating the same.

Figure 3 is a transverse sectional view illustrating the cutting element supported in an elevated position.

Figure 4 is a sectional view taken on the line 4—4 of Figure 3.

Figure 5 is a fragmentary sectional view illustrating the mounting of a sliding abutment employed in the slicing device.

Figure 6 is a detail sectional view taken on the line 6—6 of Figure 5.

Figure 7 is a sectional view taken on the line 7—7 of Figure 4.

Figure 8 is a detail sectional view taken on the line 8—8 of Figure 2.

Figure 9 is a detail sectional view taken on the line 9—9 of Figure 8.

Figure 10 is a fragmentary plan view illustrating the latch shown in Figures 8 and 9.

Figure 11 is a fragmentary sectional view illustrating one of the means for adjusting the tension of the cutting elements.

Figure 12 is a sectional view taken on the line 12—12 of Figure 3.

Figure 13 is a sectional view taken on the line 13—13 of Figure 3.

Figure 14 is an edge view illustrating a spacing plate or element for the cutting elements.

Figure 15 is a plan view illustrating the spacing plate or element.

Figure 16 is a plan view illustrating the cutting element.

Referring in detail to the drawings, the numeral 1 indicates a supporting frame which includes pairs of upstanding plates 2 and 3. The pair of plates 2 are spaced from the pair of plates 3 and are arranged adjacent the rear end of the supporting frame 1, while the pair of plates 3 are arranged adjacent the front end of the supporting frame. Arranged between the supporting plates 2 and 3 and carried by the side portions of the supporting frame is a rest or board 4 on which is adapted to be positioned the food product when it is desired to slice the latter. The rest or board 4 is arranged transversely of the supporting frame 1 and the pair of plates 3 have formed integrally therewith oppositely extending abutment flanges 5 which are suitably secured to one edge of the board or rest 4. An abutment plate 6 is slidably mounted to the pair of plates 3 and aligns with the abutment flanges 5 when in its uppermost position to cooperate therewith in forming an abutment which extends substantially the full length of the rest or board 4. The abutment plate 6 is normally urged upwardly by a spring 7 and which will permit the abutment plate to move downwardly when engaged by a cutting mechanism which will be hereinafter more fully described. The upper edge of the abutment plate 6 carries rollers 8 to be engaged by the cutting mechanism when the latter is swung downwardly for the purpose of slicing the food product upon the board or rest. The board or rest has arranged transversely thereof groups of grooves 9, the grooves of one group being arranged in closer relation than the grooves of the other group. Slots 10 are formed in the board or rest 4 and extend longitudinally thereof and intersect the grooves 9. One of the grooves 9 receives the lower edge of an abutment 11 and the latter carries depending legs 12 which extend through the slots 10 and are secured to a bracket 13 carried by the rest or board 4. Guide rods 14 are carried by the supporting frame 1 under the rest or board 4 and have slidably mounted thereon an abutment adjusting member 15 which is provided with operating rods 16 terminating at opposite sides of the supporting frame 1. The abutment adjusting member 15 is limited in endwise movement of the board or rest by the bracket 13 and includes slotted side portions 18 arranged at opposite sides of the bracket 13. The slotted side portions are to receive a removable abutment 19, the latter adapted to be moved relative to the abutment 11 so as

to accommodate small pieces of food product to be sliced by the device. It is to be understood that the abutment 19 may be applied to either one of the side plates 18 of the abutment adjusting member 15 and in this way the small pieces of food product can be placed over either group of grooves 9 so that said pieces can be severed by the cutting mechanism into slices of different thicknesses. The movable abutment 19 is similarly constructed to the stationary abutment 11 and includes depending legs removably received by the side portions 18 of the abutment operating member 15. The stationary abutment 11 divides the groups of grooves, as shown in Figure 4.

The pair of plates 2 of the supporting frame 1 are connected by a journal bar 20 for pivotally supporting the cutting mechanism and the latter consists of a pair of substantially U-shaped elements 21 connected by a bar 22 and a handle 23, the latter being located at the free end of the cutting mechanism. The pivoted ends of the frames 21 are provided with slots 24 which slidably receive a bar 25 and the latter has threaded thereto screw threaded adjusting bolts 26 which are journaled to the frame 1 and equipped with finger pieces whereby the bar may be adjusted in the slots. A similar bar 27 is fixed to the other ends of the frames 21 or adjacent to the handle 23. The bars carry pins 28 and a cutting wire 29, laced over the pins of the bars so as to form between said bars a plurality of cutting strands for severing the food product on the rest 4 into slices and which may enter the grooves of the rest so that the food product when sliced will be cut entirely through its block formation. By adjusting the bar 25 towards and from the bar 27 the tension of the cutting strands may be increased and decreased.

One of the frames 21 is provided with a socket 40 to receive a spring pressed catch or latch 30 for supporting the cutting mechanism in an elevated position, as shown in Figure 3, and after the placing of the food product on the rest or board 4 the latch is released from the respective frame 21 so that the cutting device or cutting strands thereof may be swung into engagement with the block of food product and by a further pivotal movement of the cutting mechanism in said direction the product will be severed into slices, 50 the abutment plate 6 moving downwardly under the influence of the cutting mechanism therewith.

Slotted guide plates 31 are mounted to the bars with the cutting strands arranged in the slots 55 so that said strands will be spaced from each other in accordance with the grooves 9 of the rest and board 4.

Having described the invention, we claim:

1. A slicing device comprising a support, a cutting mechanism hinged to said support adjacent one end of the latter and adapted to be swung towards and from the opposite end of the support, a rest arranged transversely of the support and within the path of movement of the cutting

mechanism and having groups of spaced grooves, a fixed abutment carried by said rest and arranged between the groups of grooves and paralleling said grooves, a movable abutment adjustably mounted on the rest and movable towards and from the fixed abutment and paralleling the grooves, and a movable abutment slidably mounted on the support and arranged at right-angles to the first-named abutment and said grooves and moved by said cutting mechanism. 10

2. A slicing device comprising a support, a cutting mechanism hinged to said support adjacent one end of the latter and adapted to be swung towards and from the opposite end of the support, a rest arranged transversely of the support and within the path of movement of the cutting mechanism and having groups of spaced grooves, a fixed abutment carried by said rest and arranged between the groups of grooves and paralleling said grooves, a movable abutment adjustably mounted on the rest and movable towards and from the fixed abutment and paralleling the grooves, a movable abutment carried by the support and located at one edge of the rest and at right angles to the first-named abutment and movable under the influence of the cutting mechanism, and spring means connected to the movable abutment.

3. A slicing device comprising a support, a cutting mechanism hinged to said support adjacent one end of the latter and adapted to be swung towards and from the opposite end of the support, a rest arranged transversely of the support and within the path of movement of the cutting mechanism and having groups of spaced grooves, a fixed abutment carried by said rest and arranged between the groups of grooves and paralleling said grooves, a movable abutment adjustably mounted on the rest and movable towards and from the fixed abutment and paralleling the grooves, a movable abutment carried by the support and located at one edge of the rest and at right angles to the first-named abutment and movable under the influence of the cutting mechanism, and spring means connected to the movable abutment.

4. A slicing machine comprising a support, a rest carried by said support and arranged transversely thereof, connected arched frames hinged to one end of the support and movable towards and from the other end of said support to overlie a product positioned on the rest, bars carried by said arched frames and one of said bars being adjustable relative to the other, pins carried by said bars, a cutting strand laced from a pin in one bar to a pin in another, and grooved plates carried by said bars to receive the strands to co-operate with the pins in maintaining the strands in spaced relation. 55
